UNITED STATES PATENT OFFICE

LEWIS EGGERT, OF TOLEDO, OHIO

OIL COMPENSATOR FOR MOLD STRIPPERS

Application filed August 30, 1929. Serial No. 389,394.

My invention relates to improvements in hydraulically operated molding machines.

One of the objects of my invention is to automatically maintain the proper quantity 5 of operating fluid in the system.

A further object is to entirely eliminate waste or loss of operating fluid from the system.

Other objects will appear hereinafter.

10 Referring to the drawing

Fig. 1 is a view, partly in section, of a molding machine and the various parts associated therewith in which my invention is embodied; and

15 Fig. 2 is a top plan view of the control valve with its cover removed to show the interior thereof.

The molding machine A shown in the drawing is known as a jolting or jarring mechanism. This machine has a table 1 at its upper end upon which the flask 2 of the mold is placed. The table 1 is intermittently jolted or vibrated up and down rapidly by air pressure, and the purpose of this operation 20 is to jolt or ram the molding sand firmly and compactly about the pattern within the flask. The pattern is mounted on a mold board or pattern plate 3 which is placed on the table 1. The flask 2, which encloses the pattern and 25 within which the molding sand is contained, is placed on the pattern plate 3 and is firmly clamped against this pattern plate by means of pneumatically operated clamps 4.

The clamps are mounted at opposite points 30 on the edge of the pattern plate and have clamping arms 5 which extend laterally to engage the upper edge of the flask and firmly clamp the flask against the pattern plate. The clamping arms 4 are movable vertically 35 either up or down to release or clamp the flask as the case may be and these arms are swung or rotated horizontally into and out of position relatively to the flask accordingly as the clamps 4 move upwardly to release the flask or downwardly to engage and clamp the flask, as set forth in my copending application Serial No. 389,393 of even date herewith. The clamps are connected by 40 means of the pipes 6 and 7 to a suitable source 45 of compressed air represented by the pipe 8.

Air pressure for the clamps is controlled by a slide valve B. The chest 9 of this valve is connected directly to the source 8 of air supply. A sliding valve member 10 is contained within the chest and is intended to 50 slide relatively to the ports 11 and 12 in the bottom wall of the chest for controlling the air for operating the clamps. The pipe 6 leading to the clamps is connected to the port 11 and the pipe 7 is connected to the port 12. 55 An exhaust port 13 is provided to which either of the other ports is connected through the chamber 14 of the slide valve member 10. These ports are so arranged that when the valve is in the position shown in Fig. 1 air 60 pressure is admitted to the port 11 from the valve chest, and the port 12 is connected to the exhaust port 13. This admits air pressure to operate the clamps downwardly for 65 clamping operation. When the slide valve is at the opposite end of the chest the port 11 is connected to the exhaust port 13 and the port 12 will be uncovered by the valve member to admit pressure to the pipe 7 to operate the clamps upwardly for releasing the 70 clamps. The slide valve is controlled by a motor driven mechanism 15, the operation of which is controlled in accordance with the 75 system of control constituting the subject matter of my copending application Serial 80 No. 389,392 of even date herewith.

Associated with the jolting mechanism is a pair of strippers C which are positioned beneath the jolting mechanism table 1. These strippers have stripper pins or rods 16 which 85 extend vertically through the table 1 and pattern plate 3 to engage the under edge of the flask. The pins are operated vertically by the strippers to raise and lower the flask with respect to the jolting mechanism table. When 90 a mold is completed the strippers are operated to elevate the mold, as indicated in dotted lines in Fig. 1, for stripping or separating the mold from the pattern. Any suitable handling machinery is then used to remove the completed mold and place an empty flask on the stripper pins for the next mold. The strippers are then lowered to place the flask 95 on the pattern plate and are allowed to remain idle while the jolting mechanism op- 100

erates and until they are again required to raise the completed mold from the table. The clamps, of course, are arranged to operate in proper timed relation to the strippers so that after the strippers lower the flask on to the pattern plate the clamps will swing into clamping engagement with the flask. The clamps release and swing out of engagement to the flask just prior to the upward operation of the strippers.

The strippers comprise stationary cylinders 17 in which plungers or pistons 18 are vertically reciprocable. The plungers have a cylindrical or cup-shaped casing 19 which extends downwardly outside of the stripper cylinder 17 to protect the mechanism from sand and dirt. The stripper pins at their lower ends are secured to ears 20 on these casings. The stripper plungers 18 contain oil or other suitable fluid 21 for hydraulically operating the plungers. The lower ends of the plungers have ports 22 which communicate with the cylinder chambers below the ends of the plungers. The upper ends of the plungers have ports 23 which are connected by the pipes 24 to the pipe 25 leading to a suitable source of pressure. When pressure is applied to the oil in the plungers the oil is forced downwardly through the ports 22 in the cylinder chamber and this forces the plunger upwardly. When the strippers are to be lowered the pressure is released, and the weight of the mold flask on the stripper pins force the plungers downwardly and force the oil from the cylinder chambers back through the ports 22 into the hollow plungers.

Pressure is applied to the oil by means of compressed air from the source 8 and controlled by the slide valve B. The pipe 25 is connected to a port 26 in the slide valve B in such manner that when the slide valve member is in the position shown in Fig. 1, the port is uncovered and pressure is admitted to the strippers. When the slide valve member is at the other end of its stroke it cuts off pressure to the pipe line 25 but instead connects the port 26 to the exhaust port 13, thus releasing the pressure and allowing the strippers to lower, as hereinbefore explained.

It has been the practice in the past to exhaust the strippers directly into the atmosphere, hence whatever air had accumulated in the lines and strippers from the previous operation would be exhausted directly into the atmosphere by the lowering of the strippers. This gave rise to operating difficulties due to the fact that the exhaust air will carry more or less oil, and after each operation a small quantity of oil will be carried out of the system. It is necessary to maintain the proper amount of oil in the strippers but under these conditions it was quite difficult to do so. Furthermore as the quantity of oil in the stripper cylinders lowered air pockets were formed above the oil in the plungers

with the result that when the remaining quantity of oil in the plungers had been forced through the ports 17 into the cylinder chambers the air would follow the oil and continue to force the plungers upwardly but the air would have the effect of violently moving the stripper plungers at the upper portions of their stroke and the strippers would reach the upper limits of their stroke with a jerk. It is very necessary that the strippers operate very smoothly and steadily and not with a jerky movement especially at the upper ends of their stroke. If the movement is jerky or violent it will jar the sand loose from the mold and damage the mold.

I overcome these difficulties by preventing the exhaust waste of oil and by automatically maintaining the strippers full of oil at all times. Instead of connecting the exhaust port to the atmosphere I connect this port by means of the pipe 27 to an oil separator and accumulator 29. This is in the form of a tank to the upper end of which the pipe line 28 connects so that the exhaust oil drops to the bottom and accumulates in this tank. The air, free from oil, exhausts to the atmosphere through a port 30 near the upper end of the tank. The lower end of this tank is connected by the pipe 31 to the pipe 25 leading to the stripper cylinders. The tank is positioned considerably above the strippers and the pipe 31 sufficiently pitched so that when the strippers are idle while the jolting mechanism is operating, the accumulated oil in the tank will drain through the pipes 31 and 25 to the strippers and maintain the proper amount of oil in the strippers. The oil flows through the pipe 31 in the direction of the arrow during these replenishing or compensating periods. However, in order to prevent the reverse flow of oil or air through the pipe 31 when operating pressure is applied through the pipe 25, I provide a check valve 32 which automatically closes the pipe 31 against reverse flow of oil or air therethrough. This check valve may be of any suitable type for the purpose. The pipe 31 also has a hand operated valve 33 of any suitable construction which is normally left open but which may be closed if desired to cut off the tank from the line for repairs or other purpose.

Thus it will be seen that waste of oil from the system is entirely eliminated, and the necessary quantity of oil for the proper operation of the strippers is constantly and automatically maintained. Any danger of jerking or violent operation of the strippers is thus entirely eliminated.

I am aware that changes in the construction and arrangement of parts may be made without departing from the scope and spirit of the invention and I reserve the right to make such changes as fairly fall within the scope of the appended claims.

I claim:

1. The combination of a fluid operated mechanism, means for applying air pressure to a liquid in said mechanism, means controlling the application of said air pressure on said liquid, means for releasing the pressure, means for accumulating the liquid from the exhaust of the air, means for returning the accumulated liquid to said mechanism when the mechanism is idle, and a check valve for preventing application of said air pressure in said accumulating means.

2. The combination of a fluid pressure operated mechanism containing a quantity of oil for operating said mechanism, means for supplying air pressure to said oil, means for releasing the air pressure and exhausting the air from said mechanism, means for separating oil from the exhaust air, means for returning the oil to the mechanism, and a check valve in said returning means for preventing back pressure in said separating means.

3. In a molding machine which has hydraulic operated strippers associated therewith containing a quantity of oil for operating the same, the combination of a pipe connecting said strippers with a source of air pressure, means for cutting off the air pressure and exhausting the air pressure from said pipe, means for collecting the oil from the exhaust air, means for returning the collected oil to the pipe whereby the collected oil may flow therethrough when the air pressure is cut off, and means in the return means for preventing back pressure in the collecting means.

4. In a molding machine which has a hydraulically operated stripper associated therewith comprising a cylinder and a plunger movable therein, and means for admitting oil to said cylinder to operate the plunger, the combination of means for applying air pressure to the oil and including a pipe line, means for cutting off the air pressure and exhausting the pressure from the cylinder, a tank for collecting oil from the exhaust, means connecting the tank with the pipe line to return the collected oil to the cylinder while the air pressure is cut off, and means in the connecting means for preventing back pressure in the tank.

5. In a molding machine which has a hydraulic stripper associated therewith comprising a cylinder and a piston operable therein, means for admitting oil to the cylinder for operating the piston, and a pipe line connected to the cylinder, the combination of a valve connecting said pipe to a source of air pressure, means operated by said valve for cutting off air pressure to said pipe and connecting the pipe to an exhaust outlet, a tank positioned above the strippers and connected to said exhaust for collecting the oil which is carried with the air from said outlet, a pipe connecting the tank with

the first mentioned pipe to return the collected oil to said first mentioned pipe when the pressure is cut off, and means in the pipe connecting the tank with the first pipe for preventing back pressure in the tank.

70

6. In a molding machine which has a hydraulic stripper associated therewith comprising a cylinder and a piston operable therein, means for admitting oil to the cylinder for operating the piston, and a pipe line connected to the cylinder, the combination of a valve connecting said pipe to a source of air pressure, means operated by said valve for cutting off air pressure to said pipe and connecting the pipe to an exhaust outlet, a tank positioned above the strippers and connected to said exhaust for collecting the oil which is carried with the air from said outlet, a pipe connecting the tank with the first mentioned pipe to return the collected oil to said first mentioned pipe, and a check valve in said second mentioned pipe for preventing the reverse flow of oil therein when pressure is applied to the first mentioned pipe.
